UNITED STATES PATENT OFFICE.

JOSEPH D. ALLEN, OF FALL RIVER, MASSACHUSETTS.

DESIGN FOR A PROTECTOR FOR SHUTTLE-BINDERS.

SPECIFICATION forming part of Design No. 27,539, dated August 17, 1897.

Application filed June 23, 1897. Serial No. 641,992. Term of patent 14 years.

To all whom it may concern:

Be it known that I, JOSEPH D. ALLEN, a citizen of the United States, residing at Fall River, in the county of Bristol and State of Massachusetts, have invented a new and original Design for Protectors for Shuttle-Binders, of which the following is a specification, reference being had to the accompanying drawings, forming a part thereof.

Figure 1 is a perspective view of a shuttle-binder, illustrating my design; and Fig. 2 is an under side view thereof.

The leading feature of my design for a protector for shuttle-binders comprises a slightly-convexed elongated head having outwardly-curved ends, longitudinal ribs along its edges on the under side, and a boss extended from the under side of the head.

Referring to the drawings, the head *a* is

shown as elongated with straight sides *a'* and outwardly-curved ends *a''*, the top of the head being slightly convex in the direction of its length. Longitudinal ribs *a'* extend along the edges *a'* on the under side of the head, and a boss *b* extends from the under side of the head at or near its center.

What I claim is—

The design for a protector for shuttle-binders, substantially as herein shown and described.

In testimony whereof I have signed my name to this specification in the presence of two subscribing witnesses.

JOSEPH D. ALLEN.
